[57]**CLAIM**

The ornamental design of a electric peeler, as shown.

DESCRIPTION

FIG. 1 is a top, front, right side perspective view of a electric peeler showing the new design;
 FIG. 2 is a right side elevation thereof;
 FIG. 3 is a left side elevation thereof;
 FIG. 4 is a bottom plan view thereof;
 FIG. 5 is a top plan view thereof;
 FIG. 6 is a front elevation thereof; and,
 FIG. 7 is a rear elevation thereof.

FIG. 6

FIG. 1

FIG. 7

FIG. 2

FIG. 3

FIG. 4

FIG. 5
